UNITED STATES PATENT OFFICE.

TAYLOR E. DANIELS, OF CHICAGO, ILLINOIS.

MANUFACTURE OF CEMENT COFFINS.

SPECIFICATION forming part of Letters Patent No. 259,373, dated June 13, 1882.

Application filed July 6, 1881. (No model.)

To all whom it may concern:

Be it known that I, TAYLOR E. DANIELS, a citizen of the United States, residing at Chicago, in the county of Cook and State of Illinois, have invented certain new and useful improvements in the Manufacture of Coffins from Marble Cement; and I hereby declare the following to be a full, clear, and exact description thereof, reference being had to the accompanying drawings, of which—

Figure 1 is a perspective view of a coffin with a portion of the side broken away, showing an internal strengthening-frame over which the coffin is molded; Fig. 2, a transverse section of the same; Figs. 3, 4, 5, and 6, detail views, and Fig. 7 a perspective view of the mold.

My invention relates to the manner in which I mold the coffin, without the use of a core, over a metallic frame having a bottom adapted to be attached to the sides of the frame after the molding has been completed with respect to the latter. Any form of frame with such a bottom may be employed; but the form shown in the drawings is suggested as strong and convenient.

In the drawings, A is the body of the coffin, B the lid, and C an embedded strengthening-frame, comprising corrugated metal plates v, having perforations u, and metallic strips or bars t, passing through slots in the corrugations transversely of the said plates. The strips t of the sides of the coffin are bolted to the strips t of the bottom, as shown at s. In addition to the transverse strips t, I sometimes employ, especially in the bottom, (although the same may be employed with advantage also in the lid and sides,) two or more longitudinal strips, r, lying in the channels of the corrugations, and likewise bolted to the strips t, as shown at s'. The ends are provided with the frame in the same manner as the sides. In order to mold the coffin, I provide the mold D with risers q and q', projecting inward from both the upper and lower edges, for the purpose of forming, while in process of molding, a gage for the thickness of cement on the interior side of the frame C.

To form the coffin the sides and ends of the

mold are all laid down to the position of the 50 side p in Fig. 7. A layer of cement is then laid upon the face of the mold of such thickness as to fall below the tops of the risers, and the sides and ends of the metal frame pressed into this layer in their proper places. After 55 this has been given a little time to set a layer of the cement is placed over the frame and is leveled off even with the tops of the risers to form the inner walls of the coffin. This in turn having also been given a little time to 60 set, the sides and ends of the mold are all raised up and secured together by means of the clamps o. The bottom E is then inserted and bolted in place to the ends of the strips t, provided these are employed. Otherwise any 65 other suitable means of fastening may be adopted. A layer of the cement of sufficient thickness is then placed on its interior surface and the whole allowed to harden, when the coffin-body will be complete with the exception of the exterior of the bottom, to finish which the coffin is removed from the mold and inverted.

The above description relates to the molding of the coffin right side up, in which case 75 the exterior of the bottom is finished last. If preferred, however, the coffin may be molded in the same manner in an inverted position, in which case the interior of the bottom is the last finished. The only difference required in 80 the construction of the mold for the latter method is that the risers adjacent to the bottom should in this case be made removable, in order that they may be taken off when the bottom is to be set in and bolted in place. Of course, 85 if formed in the latter way, the cross-strips of the bottom will be bolted to the under side of the cross-strips of the sides, as shown in Fig. 2, whereas if molded in the way first named they will be bolted to the upper side of the same. 90 One of the chief advantages of forming the coffin in this manner and setting the bottom in last is that it avoids the use of a core, which is always liable to swell and check the material, besides being always difficult to remove. Another object 95 of doing away with the core is that the cement, not having to be poured, may in that way be applied in a much thicker consistency than if

a core is used; and it is a well-known fact that the stiffer the material is worked the stronger it becomes when hardened.

The lid is formed in a separate mold in the same manner as the sides.

What I claim as new, and desire to secure by Letters Patent, is—

1. In an embedded frame of a molded coffin, the bottom E, formed of corrugated and perforated sheet metal, having cross-strips *t* passing through slots in said corrugations, and longitudinal strips *r* lying in the channels of said corrugations and bolted to the said cross-strips, substantially as described.

15 2. The method herein described of molding

a cement coffin without the use of a core, which consists in forming the sides and ends over a metal frame with the walls of the mold laid down, placing the said walls together and locking them, inserting and securing to the side frame the metal frame of the bottom, coating one side of the same with cement, and finally removing the coffin from the mold and coating the other side, substantially as described.

TAYLOR E. DANIELS.

In presence of—

WM. H. DYRENFORTH,
ADELBERT HAMILTON.
